UNITED STATES PATENT OFFICE.

EDWARD N. GUCKERT, OF TOLEDO, OHIO.

DESIGN FOR A STRINGED MUSICAL INSTRUMENT.

Application filed July 25, 1922. Serial No. 3,195. Term of patent 14 years.

To all whom it may concern:

Be it known that I, EDWARD N. GUCKERT, a citizen of the United States of America, residing at Toledo, Lucas County, Ohio, have invented a new, original, and ornamental Design for Stringed Musical Instruments, of which the following is a specification, reference being had to the accompanying drawings, forming part thereof.

The Figures 1, 2, and 3, show the top plan, side, and bottom plan views respectively, of a stringed musical instrument showing my new design.

I claim:

The ornamental design for a stringed musical instrument, as shown.

EDWARD N. GUCKERT.
